WIRE GRIPPING TOOL

Lorenzo O'Russa, Princeville, Ill., assignor to
Mathias Klein & Sons, Chicago, Ill., a corpora-
tion of Illinois

Application June 5, 1933, Serial No. 674,337

7 Claims. (Cl. 24—134)

My invention relates generally to gripping tools, and more particularly to tools of this type used by linemen for pulling wires and cables.

In certain types of gripping tools used by linemen it is sometimes difficult to disengage the gripping jaws from the cable or conductor, with the result that the lineman finds it necessary to pound the jaws with a hammer, resulting eventually in damaging the jaws. Furthermore, the gripping tool is frequently clamped to a cable in such position that it is rather difficult for the lineman to exert the force necessary to disengage the jaws. With the tool upon which my invention is an improvement it was necessary to use two hands in attaching the grip to the wire or cable. This was frequently difficult because of the position in which the lineman had to work at the top of the pole.

It is therefore an object of my invention to provide an improved gripping tool in which the above mentioned disadvantages are overcome.

A further object is to provide an improved wire gripping tool having simple means to latch the jaws in open position.

25 A further object is to provide an improved wire gripping tool in which the jaws may be easily separated.

Other objects will appear from the following description; reference being had to the accompanying drawings, in which:

Fig. 1 is a side elevation of my improved gripping tool, illustrating how the tool may be clamped to a cable by holding it in one hand, the jaws being shown in separated position;

35 Fig. 2 is a similar view showing the opposite side of the gripping tool;

Fig. 3 is a plan view thereof;

Fig. 4 is a vertical sectional view taken on the line 4—4 of Fig. 2;

40 Fig. 5 is a side elevation showing the tool in operative position gripping a cable;

Fig. 6 is a view similar to Fig. 5 showing the jaws and other parts in released position;

45 Fig. 7 is a fragmentary side elevation showing a modification of my invention, the parts being illustrated in latched position; and

Fig. 8 is a view similar to Fig. 7 showing the parts in the position assumed when the jaws are closed.

50 The gripping tool of my invention comprises a body 10 having a lower jaw 12 formed integrally therewith. An upper jaw 14 is pivotally connected to a lever 16 by a shouldered rivet 18, and is guided for translatory movement relative to the lower jaw 12 by a shouldered rivet 20, the

head 22 of which is guided in a slot 24 formed in the body 10. The lever 16 is pivotally connected to the lower jaw 12 by a shouldered rivet 26 and has its upper end pivotally connected to a pair of similar links 28 by means of a rivet 30. A torsion spring 32 is wound about a pin 34 riveted between the links 28.

One end of the spring 32 abuts against a stop pin 36 secured to one of the links 28 and the other end abuts against a notch 38 formed in the upper end of the link 16. The torsion spring thus acts in a direction to increase the angularity between the links 28 and the lever 16 and thus to force the jaws 12 and 14 together. The lower ends of the links 28 are pivotally secured to the 15 ends of a clevis 40 by a headed pin 42 which projects through the two ends of the clevis through a release arm 44, and through an elongated slot 46 formed in the body 10. The pin 42 may be secured in position by a cotter pin 48.

The release arm 44 has a pair of ears 50 formed thereon which engage the clevis 40 so that the arm in effect forms an extension of one of the shanks of the clevis. A link 52 has one end pivotally connected to the release arm 44 by a rivet 54. The link 52 has an elongated slot 56. A projection 58 of the pin 20 extends through the slot 56 and is adapted to engage in a notch 60 formed in the release arm 44. The forward end of the release arm has an inclined surface 62 which aids in the engagement of the notch over the projection 58. The link 52 has an inclined end surface 64 which is adapted to engage one of the links 28 and thereby limit the swinging movement of the release arm 44 and clevis 40 in a downward direction (Fig. 2).

In using the gripping tool the operator grasps the clevis in one hand as shown in Fig. 1, and pulls rearwardly on the lower jaw 12 until the projection 58 engages in the notch 60 of the release arm 44, whereupon the parts will be latched in the position shown in Fig. 2. The lineman may then reach out and attach the gripping tool to a conductor or cable, as indicated in Fig. 1. When the jaws have been placed about the wire, 45 they may be released by swinging the clevis upwardly (Figs. 1 and 2) relative to the body 10, whereupon the hook portions of the release arm 44 will no longer engage the projection 58, and the spring 32 will act to move the jaws into 50 clamping position about the wire or cable. Then the rope 66 may be pulled taut by means of block and tackle, or otherwise, to tighten the cable or wire. The rope 66 being attached to the clevis 40 will tend through the action of the links 28 55

and lever 16 to force the jaws firmly into engagement with the cable or wire, the clamping pressure of the jaws increasing in proportion to the strength of the pull on the rope.

5 Frequently the jaws become so tightly clamped about the wire or cable that it is difficult to release them. This is especially true if the clamp is attached to a wire at the top of a telephone pole. With the clamp of my invention the operation of releasing the clamp is very simple, since it is necessary merely to swing the clevis from the position shown in Fig. 5 to the position shown in Fig. 6 in the direction of the arrows. By swinging the clevis in this direction the link 52 is pulled 10 rearwardly and downwardly until the end of the slot 56 engages the projection 58. Continuance of the swinging movement of the clevis forces the links 28 upwardly and forwardly, thereby swinging the lever 16 clockwise (Figs. 5 and 6) 15 and separating the jaws 12, 14. There is a considerable mechanical advantage in the link and lever arrangement so that the separation of the jaws requires but little physical effort.

The modification shown in Figs. 7 and 8 is 20 quite similar to that previously described, and due to the close similarity the clamp has not been illustrated in complete detail, and for the same reason the parts which correspond to those previously described have been given the same 25 reference characters and will not again be described in detail.

In Figs. 7 and 8 an arm 70 pivoted on the pin 42 is secured to the clevis 40 by ears 72 so as to swing therewith. A link 74 having a longitudinal slot 76 is pivoted to the end of the arm 70 by a shouldered rivet 78. A shouldered screw 80 projects through the slot 76 and is threaded in the body 10. A pin 82 is secured in the body 10 and is adapted to engage in a notch 84 formed adjacent the end of the link 74. As shown in Fig. 7, the jaws of the gripping tool may be clamped in open position by engaging the pin 82 in its notch 84 thereby holding the clevis in its forward position in its slot 46. When the clevis is swung upwardly (clockwise, Figs. 7 and 8) the arm 70 swings the link 74 counterclockwise about the screw 80, thereby disengaging the notch in the link 74 from the pin 82. Thereupon the spring 32 of the clamp will force the parts to the position 30 shown in Fig. 8, clamping the jaws about a cable. The jaws may be released by swinging the clevis clockwise from the position shown in Fig. 8, whereupon the link 74 will pull against the screw 80 and the pivot pin 42 thereby be pulled forward, forcing the links 28 upwardly to release the 35 jaws.

While I have shown and described particular embodiments of my invention it will be readily understood by those skilled in the art that variations may be made in the constructions disclosed without departing from the basic features of my invention. I therefore do not wish to be limited to the precise construction disclosed but wish to include within the scope of my invention all such 40 modifications and variations which will readily suggest themselves.

What I claim as new and desire to secure by United States Letters Patent, is:

1. In a wire gripping tool, the combination of 45 a pair of jaws conformed to grip a wire, one of said jaws having a slot formed therein, a lever pivotally connected to said jaws for moving them into and out of engagement, means to maintain said jaws in substantial parallelism when moved 50 relative to each other by means of said lever, a

link having one end thereof pivotally secured to said lever, a clevis, a pivot pin pivotally securing said clevis to the other end of said link and projecting through said slot formed in one of said jaws, a spring tensioned to move said jaws to closed position, a slotted member having one end pivotally connected to said clevis, and a pin projecting through the slot in said member and secured in one of said jaw members, said slotted member and pin forming a lost motion stop for 55 said clevis whereby the latter when pivoted may exert a force upon said link thereby to separate said jaws.

2. In a wire gripping tool, the combination of a pair of jaws conformed to grip a wire, one of said jaws having a slot formed therein, a lever pivotally connected to said jaws for moving them into and out of engagement, means to maintain said jaws in substantial parallelism when moved relative to each other by means of said lever, a link having one end thereof pivotally secured to said lever, a clevis, a pivot pin pivotally securing said clevis to the other end of said link and projecting through the slot formed in one of said jaws, a spring tensioned to move said jaws to closed position, and an element connected to said clevis and operated by swinging movement thereof to cause said pivot pin to slide in said slot and through said link to separate said jaws.

3. In a gripping tool, the combination of a pair of jaws for gripping a wire, a clevis pivotally and slidably connected to one of said jaws, a linkage connecting said clevis and jaws whereby a pull on the clevis in the longitudinal direction of said jaws will cause clamping engagement thereof with a part to be gripped, a latch to hold said jaws in separated position, and an element connected to said clevis and operated by swinging movement thereof to separate said jaws.

4. In a device of the class described, the combination of a pair of jaws conformed to grip a wire therebetween, a clevis for attachment to a rope or cable for exerting a pulling force on said jaws, said clevis having an extension, a force multiplying linkage connecting said clevis and said jaws to cause the latter to grip a wire when a pull is exerted upon the former, and a link having a pin and slot connection with one of said jaws and pivotally connected to the extension of said clevis, said link forming a movable pivot for said clevis when the latter is swung out of alignment with said jaws, thereby permitting application of force to said linkage to separate said jaws.

5. In a gripping tool, the combination, of a pair of jaws, means for relatively moving said jaws, an element to maintain said jaws in substantial parallelism when moved relative to each other by said means, a clevis pivotally connected to said means for applying a force thereto, a spring tensioned to move said jaws to closed position, a slotted link having one end pivotally connected to said clevis, and a pin projecting through the slot in said link and secured in one of said jaw members, said link and pin forming a lost motion stop for said clevis whereby the latter when pivoted may exert a force upon said pair of links thereby to separate said jaws.

6. In a gripping tool, the combination of a pair of jaws, means for relatively moving said jaws, an element to maintain said jaws in substantial parallelism when moved relative to each other by said means, a clevis pivotally connected to said means for applying a force thereto, a spring tensioned to move said jaws to closed position, and an element connected to said clevis and op- 75

erated by swinging movement thereof to cause said clevis to move laterally and by force applied to said element to separate said jaws.

7. In a device of the class described, the combination of a pair of jaws conformed to grip a wire therebetween, a clevis arranged to be attached to a rope or cable for exerting a pulling force on said jaws, a force multiplying linkage connecting said clevis and said jaws to cause the

10 latter to grip a wire when a pull is exerted upon

the former, a link having a pin and slot connection with one of said jaws and pivotally connected to said clevis, said link forming a movable pivot for said clevis when the latter is swung out of alignment with said jaws, thereby permitting application of force to said linkage to separate said jaws, and means associated with said link for latching said jaws in open position.
